United States Patent Office

Des. 194,707

Patented Feb. 26, 1963

194,707

COMPASS HOUSING

Wallis E. Stuart III, 298 King St., Cohasset, Mass.

Filed Feb. 9, 1962, Ser. No. 68,737

Term of patent 14 years

(Cl. D52—6)

Fig. 1.

Fig. 2.

Fig. 3.

Fig. 4.

Fig. 5.

FIG. 1 is a front perspective view of a compass housing, showing my new design;

FIG. 2 is a plan view thereof;

FIG. 3 is a side elevational view thereof;

FIG. 4 is a front end elevational view thereof; and

FIG. 5 is a rear end elevational view thereof.

I claim:

The ornamental design for a compass housing, substantially as shown.
